UNITED STATES PATENT OFFICE.

WILLIAM HENRY PARHAM, OF PADUCAH, KENTUCKY.

BUNG-FAUCET.

SPECIFICATION forming part of Letters Patent No. 367,999, dated August 9, 1887.

Application filed December 4, 1886. Serial No. 220,715. (No model.)

To all whom it may concern:

Be it known that I, WILLIAM HENRY PARHAM, a citizen of the United States, residing at Paducah, in the county of McCracken and State of Kentucky, have invented a new and useful Improvement in Bung - Faucets, of which the following is a specification.

My invention relates to improvements in bung-faucets, and it has for its object, first; the provision of a device whereby the liquids may be drawn from a barrel or cask without waste, and, second, the provision of a faucet which may be more readily applied than those now in general use.

The invention consists in certain novel constructions and arrangements of parts, as fully set forth hereinafter and claimed.

In the accompanying drawings, Figure 1 is a perspective view of a cask, showing the manner of applying my improved bung - faucet. Fig. 2 is a front elevation of my faucet with the cut-off shown in its open position. Fig. 3 is a vertical longitudinal section on the line $x-x$ of Fig. 2, showing the ventilating-duct in dotted lines and the faucet in position within the barrel. Fig. 4 is a horizontal section on the line $y-y$ of Fig. 3. Fig. 5 is a detail sectional view of the annular packing-ring. Fig. 6 is a rear elevation with the vent - pipe removed.

Referring to the drawings, in which similar letters denote corresponding parts in all the figures, A is the spout, substantially conical in form, provided on one side of its peripheral edge, at the inner end, with a vertical bifurcated extension forming the arms B B, each of which has a slot, C.

D is a cam-lever consisting of the arm or handle d and the cam d' , shaped as shown, for a purpose to be hereinafter explained. Said cam is provided at each side with the trunnions E, which are designed to fit in the slots C of the arms B, and are adapted to engage in the notches c in the upper wall of the slots C. F is the ordinary cut off, journaled in projecting lugs G and having the spring H, all of the ordinary construction and operation.

f is the usual packing-ring for the cut - off.

I is an annular groove provided in the rear side of the faucet-spout A, for the reception of the rubber packing-ring or gasket K. Said

packing-ring K is wider, or formed with an enlargement, at its upper portion, K', and is beveled from the peripheral edge at that point to the inner edge or wall of the circular opening K², made in the ring.

L is a vent-pipe having an abrupt bend at l, and vertical portion l'. l' is a horizontal portion of said pipe L, the end of which, l, is threaded to enter a threaded opening in the lug N, located on the interior upper side of the opening in the spout A. The opening in said lug N communicates with a ventilating-duct, O, made in the thickness of the wall of the spout. Said duct passes along the entire length of the spout A, and has a vent, P, in the outer end thereof, as shown. Said vent P is closed by the cut-off F at the same time that the spout is closed. The duct O, in passing the length of the spout A, makes a quarter-turn, or thereabout, around the opening of said spout. The duct then has a regular downward slant from the opening in the lug N to the vent P, as shown in Fig. 3. This downward slant enables all liquid which may possibly enter the pipe L while placing the faucet in position to escape through the vent P.

The operation of my invention is as follows: When it is desired to empty a cask, the bung is drawn and the vent-pipe L is passed through the opening, and the packing-ring or gasket K is pressed against the cask around the sides of the outlet-opening. The entire faucet is then pressed upwardly, so as to align the outlet-opening of the spout with the opening in the cask. In order to produce said alignment, it is necessary that the horizontal portion l' of the vent-pipe L should be pressed up against the upper edge of the opening in the cask, as shown in Fig. 3. The distance between the vertical portion l' of the said pipe L and the thickest part of the beveled portion K' of the packing-ring K being slightly less than the thickness of the stave of the cask, it will be seen that the said rubber packing-ring will be compressed at the said thickest or beveled portion K' when the faucet is in position. The distance between the vertical portion l' of the pipe L and the beveled portion of the packing-ring may be varied to suit the thickness of the staves by screwing the said pipe L more or less into the lug N. Having firmly wedged

the upper edge of the bung-opening between the vent-pipe L and the said thick portion of packing-ring K, I now engage the trunnions of the cam-lever D in a pair of the aligned notches c in the slots C of the bifurcated projection B and force the lever-arm d toward the cask. The action then is as follows: The cam-lever D being above and adjacent to the beveled portion K' of the packing-ring K, the act of moving 5 the lever-arm d toward the cask forces the bifurcated arm B from said cask, and the stave of the cask, at the upper edge of the bung-opening, being firmly clamped between the vertical portion l' of the vent-pipe and the said thick portion K' of the packing-ring K, it will be readily seen that the lower portion of the packing-ring K will come in close contact with the said stave around the opening therein and be compressed between the rear end of the 10 faucet and the said stave, thus forming a tight joint. I provide in the slots C of the arms B notches c of different depths, to allow of the adjustment of the cam-lever D, it being obvious that deeper notches are necessary when the faucet is applied to casks having thick staves than are necessary when faucet is applied to casks having thin staves. Having 15 now firmly adjusted the faucet to the cask, said cask is rolled over until the faucet is on the side thereof and all is in readiness for operation. When the cut-off F is turned to the position indicated in Fig. 2, the vent P is opened, allowing the air to enter the duct O, pass through the opening in the lug N and up the pipe L into the interior of the cask above the liquid. The said liquid then flows from the spout A in a steady stream, which may be cut off at any 20 time without causing any subsequent dripping.

If the pipe L is not of sufficient length to 25 reach a point above the top of the liquid in the cask, an extension therefor may be added, as will be obvious.

When faucets of the ordinary construction are used, it is necessary to supply a vent in the 30 cask by which air may enter to allow the liquid contents to be withdrawn. Such vents not being provided with the means to close them, flies, ants, &c., are admitted to the cask. In my improved faucet the air-vent is only 35 open during the actual operation of drawing the said contents, said vent being closed by the cut-off for the faucet-spout.

Another advantage which my faucet possesses over those now in general use lies in the 40 fact that the said vent is a part of the faucet. Therefore said vent is only in the cask when needed.

My faucet possesses still another advantage, 45 in that it is much more readily and securely applied to a cask or barrel than is the case with other faucets.

Having thus described the construction and 50 operation of my invention, what I claim, and desire to secure by Letters Patent of the United 55 States, is—

1. In a bung-faucet, the combination of the

spout A, having duct O and vent P, with the vent-pipe L, provided with the vertical portion l' and the threaded end l'', communicating with the duct O, the vertical arms B, slots C 60 therein, notches c, of different depths, in the slots, cam-lever D, provided with the trunnions E to fit in the slots and engage the notches, and the rubber packing-ring K, provided with the beveled portion K', substantially as and 75 for the purpose set forth.

2. In a bung-faucet, the combination of a spout having an angular device, as L, connected at one end thereto and engaging with the edges of the bung-opening in the cask, and 80 a vertically-adjustable clamping-lever, D, having an adjustable fulcrum-connection with the spout and bearing against the outer side of the cask to draw the device L into close contact with the cask, as and for the purpose described. 85

3. In a bung-faucet, the combination of a spout having an air-duct, an angular vent-tube adjustably connected to the spout and communicating with the air-duct, and a clamping cam-lever, D, having an adjustable fulcrum-connection with the spout, as and for the purpose described. 90

4. In a bung-faucet, the spout having the vertical arms provided with the longitudinal aligned slots and the notches in the slots, and communicating therewith, in combination with an adjustable lever having the trunnions sliding in the slots to adjust the lever and adapted to take into the notches and thereby form fulcrums for the lever, and an angular device, as L, connected to the spout, as and for the purpose described. 95

5. In a bung-faucet, a spout and a compressible packing-ring or gasket interposed between the spout and cask, and having the inner or rear face beveled outwardly from the upper edge of the opening therein to the periphery of the ring, as at K', in combination with a device, as L, for connecting the spout to the cask, and an adjustably-fulcrumed cam-lever having its fulcrum-connection with the spout at a point thereon in close proximity to the beveled portion of the gasket, as and for the purpose set forth. 105

6. In a bung-faucet, a spout, A, having a longitudinal air-duct, which is interiorly threaded at its rear extremity, in combination with a vent-tube having at its lower end a bent threaded arm, e, which is screwed into 110 the rear threaded end of the air-duct and thereby adjustably connected to the spout, a cut-off working over the open end of the spout and the air-duct therein, and a clamping-lever having an adjustable fulcrum-connection with the spout, as and for the purpose described. 115

7. In a bung-faucet, a spout, A, having the air-duct O arranged longitudinally thereon and on one side of the central passage or channel in the spout, the front end of the said duct being inclined downwardly toward the front end of the spout, through which the said duct 120

opens and thereby forms the vent P, in combination with the vent-tube adjustably connected to the spout, a clamping-lever connected to the spout, and a cut-off working 5 over the open end of the central channel and vent P in the spout, as and for the purpose described.

8. In a bung-faucet, the spout A, having vent-pipe L, provided with the abrupt bend l, 10 combined with the packing having the bev-

eled portion K', and the cam-lever D, having an adjustable fulcrum-connection with the spout, substantially as described.

In testimony that I claim the foregoing as my own I have hereto affixed my signature in 15 presence of two witnesses.

WILLIAM HENRY PARHAM.
